UNITED STATES PATENT OFFICE.

HEINRICH THIEL, OF RUHLA, GERMANY, ASSIGNOR TO FRIED. KRUPP AKTIEN-
GESELLSCHAFT, OF ESSEN-ON-THE-RUHR, GERMANY.

MECHANICAL TIME-FUSE.

1,372,574.

Specification of Letters Patent. Patented Mar. 22, 1921.

Application filed November 19, 1920. Serial No. 425,101.

To all whom it may concern:

Be it known that I, HEINRICH THIEL, residing at Ruhla, Germany, a citizen of the German Republic, have invented a certain 5 new and useful Improvement in Mechanical Time-Fuses, of which the following is a specification.

My invention relates to mechanical time fuses, in which the percussion pin which is 10 rotatable on its axis is supported in inoperative position by means of a cam attached to it and a fixed support in contact with said cam. In time fuses of this type used heretofore usually a releasing shaft journaled at 15 both ends was interposed between the percussion pin and the arm which releases the percussion pin, when operated by the time element of the fuse. This arrangement has the disadvantage that this releasing shaft is 20 easily bent owing to the enormous forces which come into action during the firing of the projectile resulting in the jamming of the shaft in its bearings so that this releasing shaft does not properly function when 25 the time comes to bring the percussion pin into action. The subject matter of the present invention refers to a mechanical time fuse of this type in which this disadvantage is avoided and in which the releasing mechanism is materially simplified. 30

In the accompanying drawings, an example of my invention is illustrated. In these drawings:

Figure 1 is a transverse section of the elements in question of the time fuse on the line A—B in Fig. 2;

Fig. 2 shows the elements of this mechanism in longitudinal, vertical section;

Fig. 3 shows a transverse section similar to 40 that shown in Fig. 1 with the elements in the position after the percussion pin has operated.

Fig. 4 shows a rear view of the lower portion of the fuse shown in Fig. 2, and

Fig. 5 shows a similar view of the elements shown in Fig. 4 after the percussion pin has operated.

The percussion pin 1, rotatable on its longitudinal axis as shown and actuated by 50 spring 2, is provided with a cam 3 provided with an inclined face 4 which rests upon the cone-shaped top 7 of a pin 5 rigidly supported on the casing plate 6 of the fuse.

The upper portion of percussion pin 1 is squared as shown at 8 and this end of the pin is located in the releasing arm 9 such that it can longitudinally slide therein but is prevented from rotation except through the rotation of arm 9. Arm 9 may be held in the position in which cam 3 rests upon pin 5 by any well known timing mechanism employed in such devices so that percussion pin 1 is prevented from rotation until the time element brings about the release of arm 9. In order to secure the time fuse against premature action, for instance during the transport of the projectile, percussion pin 1 is secured against longitudinal motion toward the percussion cap by means of a lock 11, rotatable on pin 12 and actuated to release 70 the pin by means of centrifugal force. This locking element 11 engages the percussion pin 1 underneath a collar 15 provided on the pin. The contour of the locking element 11 is such that the portion 16 of this element 75 adjacent to pin 1 when the element is swung out by centrifugal force as shown in Fig. 3, is recessed so as to clear the path of collar 15. After the projectile is fired, the locking element 11 swings outwardly as shown 80 in Fig. 3. Now, the pin is only held by releasing arm 9 which prevents the cam 3 from sliding off pin 5 until the time arrives at which the time element of the fuse (not 85 shown here) releases arm 9. At this moment, arm 9, which is simultaneously under the influence of the centrifugal force and of spring 2 swings outwardly, aided by the inclined face 4 of cam 3 so that the percussion pin 1 rotates whereby cam 3 slides off 90 bolt 5 whereupon the pin is free to strike the percussion cap (not shown) with its point 17.

I claim—

1. In a mechanical time fuse, a percussion pin adapted to rotate on its axis and to slide in the direction thereof, a cam on said pin, a fixed support contacting with and thereby supporting said pin, an operating arm directly connected to said pin, said operating arm adapted to rotate said pin to release 100 said cam from its support, the connection between said pin and said arm permitting said pin to move relatively to said arm in a longitudinal direction after the release has occurred. 105

2. In a mechanical time fuse, a percussion

pin adapted to rotate on its axis and to slide in the direction thereof, a cam on said pin having a face inclined to the pin axis, a fixed support contacting with said inclined face and thereby supporting said pin, an operating arm directly connected to said pin and adapted to rotate it to release said cam from its support, the connection be-

tween said pin and said arm permitting said pin to move relatively to said arm in a longitudinal direction after the release has occurred.

HEINRICH THIEL.

In presence of—

EMIL DÜRER,

AUGUST HARTMANN.
